UNITED STATES PATENT OFFICE

163,510

CHRISTMAS TREE FAIRY DOLL ORNAMENT

Susan A. Beasley, Hamilton, Ontario, Canada

Application November 4, 1950, Serial No. 12,854

Term of patent 3½ years

(CL. D29—1)

To all whom it may concern:

Be it known that I, Susan A. Beasley, a subject of the King of Great Britain, residing at the city of Hamilton, in the county of Wentworth, in the Province of Ontario, Canada, have invented a new, original, and ornamental Design for Christmas Tree Fairy Doll Ornament, of which the following is a specification, reference being had to the accompanying drawing, forming a part hereof.

Fig. 1 is a front elevational view of a Christmas tree fairy doll ornament showing my new design.

Fig. 2 is a side elevational view thereof.

I claim:

The ornamental design for a Christmas tree fairy doll ornament, as shown.

SUSAN A. BEASLEY.
